UNITED STATES PATENT OFFICE.

THOMAS LITWILLER, OF TREMONT, ILLINOIS.

WIRE-FENCE FABRIC.

REISSUED

SPECIFICATION forming part of Letters Patent No. 769,223, dated September 6, 1904.

Application filed November 15, 1902. Renewed November 9, 1903. Serial No. 180,396. (No model.)

To all whom it may concern:

Be it known that I, THOMAS LITWILLER, a citizen of the United States, residing at Tremont, in the county of Tazewell and State of Illinois, have invented certain new and useful Improvements in Wire-Fence Fabrics; and I do hereby declare that the following is a full, clear, and exact description of the invention, which will enable others skilled in the art to which it appertains to make and use the same.

This invention has reference to wire fencing.

The object of the invention is to provide a wire fence formed of body-wires and selvage-wires, and connected or intertwined with the body and selvage wires are wire stays that bear diagonally to the body of the fence and are intertwined with the selvage and body wires where they intersect alternately in opposite directions.

The invention has for its further object a fence which is durable and cheap at first cost and that may be and is produced by a machine wherein the fabric is continuously drawn out and reeled without interruption during the feeding of and intertwisting the stay-wires with the longitudinal wires forming the body of the fabric.

Figure 1, drawn to a small scale, shows a strip of fencing embodying my improvements as it appears when placed in the field. Fig. 2, drawn to a larger scale, shows more clearly the detail construction of the fence and is a section from Fig. 1 bounded by the dotted line shown in such figure.

The fence comprises what will be hereinafter known as the "selvage-wires" 1 and the "body-wires" 2, arranged at suitable intervals apart from each other intermediate the selvage-wires to present a uniform or graduated mesh, as may be desired, and 3 indicates stays, preferably of wire, spaced at suitable intervals apart and adapted, as shown, to be intertwined with the selvage and body wires, which together comprise my improved fencing.

Attention is called to the selvage-wires 1,

which I have shown as twisted cable-strands; but it is to be understood that the selvage-wires may comprise each a single wire of suitable strength in proportion to the heft of the body-wires common in all fences.

In making the fence, which is continuously fed from the machine, producing a finished product without interruption, which ordinarily occurs at intervals after placing each stay, the bobbins which carry the wire comprising the stays are fed across the selvage and body wires obliquely or diagonally to the longitudinal bearing of these wires, and hence the finished product, as shown in Fig. 1, shows the stays bearing in diagonal lines, presenting a rectangular mesh having horizontal top and bottom wires and sloping or slanting end wires. By this mode a series of carriages are provided, carrying bobbins, each containing a spool of wire which forms the stay, and the carriages will follow each other at intervals apart, moving across the body and selvage wires, and successively cause their stay-wires to be intertwined with coinciding body and selvage wires alternately in opposite directions—for example, follow the first complete stay-wire 3 to the left of Fig. 1, leading from the lower selvage-wire 7. It is intertwined with the selvage 1 at *a* a portion of its length. It is then led diagonally to the adjacent body-wire 2 and intertwined therewith, as at *b*, in a direction opposite to that shown at *a*. The wire 3 is then led diagonally to the next adjacent body-wire 2 and continued to be so led until it coincides with the upper selvage-wire 1, with which it is intertwined or wrapped around, when the wire is cut shortly after the spool leaves the selvage, leaving the free end of the stay directed longitudinally, as at 4. The appearance of the stay-wires at the bottom of the fence will be the same as at the top or upper end, and the stay just referred to as it is brought coincident with each succeeding body-wire is intertwined therewith in opposite directions, as at *a* and *b*—that is, the stay-wires are intertwined with the body-wires in opposite directions by leading the

said stay-wires first over the body-wires and then under the same, as seen in the figures, which is accomplished by rotating the twisters of the carriages first in one direction and then 5 in an opposite direction. By following each stay from left to right the intertwists appear in opposite directions, but follow a series of twists in a diagonal line from right to left, crossing a series of stays and body-wires, and 10 the twists all appear similar.

Attention is now called to the body-wires, which are slightly drawn out of horizontal line where the twist is made with the stay-wires occasioned by the peculiar manner in 15 which the stays are carried. The twists slant in one direction, while that portion of the body-wires intermediate the twists, as at *c*, slant in an opposite direction. Attention is also called to the variations in the slant of the 20 stays or that portion of each stay intermediate or connecting the body and selvage wires. The slant is greater where adjacent longitudinal wires are closest and less where they are farthest apart. However, the exact incline 25 or diagonal position of the stays may be modified, as also the arrangement of the body-wires, and it may be convenient instead of twisting both the body and stay wires where they are coincident to twist only the stay around 30 the body-wires, or vice versa, or twist the stay and partially twist the body-wire, all of which, it is believed, will come within the scope of the invention. The alternate stays, beginning with the second, have their twists with the 35 selvage-wire just opposite to those of the first stay. This is occasioned by the fact that these stays are not introduced into the fence until after the preceding stay-wires and their carriages are coincident with the lowermost 40 body-wire. A series of carriages are employed and ushered into use in this manner until the carriage carrying the first-mentioned stay has passed the upper selvage-wire and caused to be twisted therewith its stay, when 45 it assumes its position with the lowermost selvage and each step of the process carried out as hereinabove set forth. In this way adjacent stay-wires where they are intertwisted with a body or selvage wire will be 50 in opposite directions, not only vertically, but longitudinally. (See Fig. 2.)

Having thus fully described my invention, what I claim, and desire to secure by Letters Patent of the United States, is—

55 1. A wire-fence fabric, composed of body-wires and selvage-strands, of stay-wires extending obliquely across the body-wires from selvage-strand to selvage-strand and at each succeeding point of intersection with the selvage-strands and body-wires twisted therewith alternately over and under, substantially as described.

2. In a wire-fence fabric, the combination of a series of body-wires, and stay-wires, extending obliquely across the body-wires from 65 selvage to selvage the twist of adjacent stays with corresponding body-wires being alternately over and under and having the twists measured along the body-wires in the same direction, substantially as described. 70

3. In a wire-fence fabric, the combination of a series of body-wires and selvage-strands, stay-wires extending obliquely across the series of body-wires and twisted with adjacent body-wires alternately over and under, and adjacent stays twisted with corresponding body-wires alternately over and under and 75 having the twists measured along the body-wires in the same direction, substantially as described. 80

4. In a wire-fence fabric, the combination of a series of body-wires and selvage-strands, stay-wires extending obliquely across the body-wires from selvage to selvage and twisted with adjacent body and selvage wires, alternately over and under and having the twists of the stays and body-wires measured along the body-wires in the same direction, and short longitudinally-presented extensions of each stay where they are twisted with the selvage-strands, substantially as described. 85

5. In a wire-fence fabric, the combination of a series of running-wires, of stay-wires bearing obliquely across the running-wires and twisted with the running-wires where they 95 intersect, the twist of the stay-wires as they bear diagonally across the fabric from left to right being alternately over and under and having their twists uniform in a line bearing diagonally across the fabric from right to left, 100 substantially as described.

6. In a wire fence, the combination of a series of body-wires and selvage-wires, stay-wires intertwisted with the body and selvage wires and alternate stay-wires where they intersect with the body and selvage wires being intertwisted therewith alternately over and under, that portion of the body-wires where they intertwist with the stay-wires inclined slightly out of horizontal, while that portion 105 of each body-wire intermediate each twist is inclined slightly out of horizontal but in an opposite direction to the incline of the twisted portion. 110

7. A wire fence, composed of body-wires and selvage-wires, of stay-wires extending across the body-wires from selvage-wire to selvage-wire and each stay at each succeeding point of intersection with the selvage and body wires twisted therewith alternately over 115 and under, the stay-sections between the selvage and body wires bearing in oblique lines and always in advance of their twists with the lower selvage-wire and behind their twists 120

with the upper selvage-wire, substantially as described.

8. In a wire-fence fabric, the combination of running-wires, stay-wires extending obliquely across the running-wires, adjacent stay-wires where they intersect with corresponding running-wires twisted therewith alternately over and under both across the run-

ning-wires and measured along corresponding running-wires, substantially as described.

In testimony whereof I affix my signature in presence of two witnesses.

THOMAS LITWILLER.
